MOBILE SWIMMING POOL

Gerald H. Croushore, 128 Mohawk Drive, Cranford, N.J.

Filed June 28, 1963, Ser. No. 75,570

Term of patent 14 years

(Cl. D34—5)

FIG. 1 is a perspective view of a mobile swimming pool showing my new design.

FIG. 2 is a top plan view of such design.

FIG. 3 is a perspective view looking from the rear side of the mobile swimming pool showing my new design.

Both longitudinal sides of the article are identical.

I claim:

The ornamental design for a mobile swimming pool, substantially as shown and described.
